UNITED STATES PATENT OFFICE.

JASPER CURRY, OF BUFFALO, TEXAS.

WHIFFLETREE-CLIP.

SPECIFICATION forming part of Letters Patent No. 694,254, dated February 25, 1902.

Application filed July 31, 1901. Serial No. 70,415. (No model.)

To all whom it may concern:

Be it known that I, JASPER CURRY, a citizen of the United States, residing at and whose post-office address is Buffalo, in the county 5 of Leon and State of Texas, have invented new and useful Improvements in Whiffletree-Clips, of which the following is a specification.

This invention relates to whiffletree-clips; and the primary object thereof is to provide a 10 inexpensive, durable, and efficient clip which may be easily applied to a singletree or doubletree, and, further, to dispense with the lap-link now in common use.

The peculiar construction of the device will 15 be clearly described hereinafter, illustrated in the accompanying drawing, and claimed.

In the drawing, Figure 1 is a top plan view of a clip constructed in accordance with my 20 invention, a portion of the whiffletree being illustrated to show the application. Fig. 2 is an end elevation of the same.

Referring now to the drawings by numerals of reference, 1 designates a circular and split band having lugs 2 and 3 at its respective 25 edges, which adapt it to be engaged by a bolt 4, whereby said band may be securely fastened to the end of a singletree. From the

front side of the band 1 projects an integral U-shaped loop 5, having a perforation in which is loosely pivoted a hook 6, provided 30 with a head 7 to limit the outward movement of said hook. This hook is so fastened that it may turn readily to provide for the vibration of the trace or draft-harness.

It will be noted that the band 1 is constructed, preferably, of spring metal and may be applied to a plow-clevis or the end of the whiffletree through the medium of the bolt 4 and may be readily removed therefrom.

Having thus fully described my invention, 40 what I claim as new, and desire to secure by Letters Patent, is—

A whiffletree-hook comprising a split band formed integral with perforated lugs at its rear edges and with an U-shaped loop at its 45 front, a bolt connecting the lugs, and a hook pivoted in the loop and having a retaining-head.

In testimony whereof I affix my signature in presence of two witnesses.

JASPER CURRY.
